his attorney

UNITED STATES PATENT OFFICE.

CHARLES C. BLAKE, OF BROOKLINE, MASSACHUSETTS.

METALLIC FASTENING INSEAM.

Application filed February 18, 1918. Serial No. 217,770.

The present invention relates to means for connecting members together such, for instance, as the shoe upper, welt and insole of a welt shoe, and more particularly to a 5 metallic fastening connecting means which may be used instead of stitches for the inseam of a Blake welt shoe.

The Blake welt shoe is provided with a welt, upper and insole united by a sewed inseam with the unexposed faces of the welt and upper in the same plane so that the outsole may be secured to the welt in contact with the entire surface of the unexposed face of the insole. With this construction the objectionable plastic filling between the insole and outsole and the discommodeing marginal abutment essential in Goodyear welt shoes are avoided. While the Blake welt shoe is more flexible, durable and 20 comfortable than any other type of welt shoe, for use by our soldiers in the trenches, where sewed inseams quickly rot under the watery conditions existing therein, it is desirable that the sewed inseam be replaced 25 by a metallic fastening inseam.

The principal object of the present invention is to produce a shoe, having all the beneficial advantages of a sewed Blake welt shoe, in which the upper, insole and welt are 30 united by a metallic fastening inseam.

To the accomplishment of this object, and such others as may hereinafter appear, the features of the invention relate to certain constructions, arrangements of parts and methods of manufacture hereinafter described and set forth broadly and in detail in the appended claims which possess advantages readily apparent to those skilled in the art.

I have selected an insole and the manner of its connection with the shoe upper and welt of a welt shoe for the purpose of illustration as it shows the invention in its best form at present devised. It will be readily 45 apparent, however, that in its broadest aspects the invention may be utilized to unite various components of other kinds of shoes and articles.

The various features of the present invention will be readily understood from an inspection of the accompanying drawings, in which:

Figure 1 is a plan showing the metallic fastening inseam which unites the welt, upper and insole of a welt shoe;

Fig. 2 is a detail in perspective, partly in section, of a lasted shoe and of a welt which is being united to the lasted shoe by a metallic fastening inseam;

Fig. 3 is a detail in sectional plan showing a metallic fastening which has been inserted into the awl cut and then driven against the anvil by the awl;

Fig. 4 is a similar view to Fig. 3 showing the metallic fastening being driven into its final clenching position by the awl guide which acts as a driver;

Fig. 5 is a detail in perspective showing the manner in which the fastening is formed from a strip of stock;

Fig. 6 is a detail in perspective of a metallic fastening illustrating the form it assumes in the finished shoe;

Fig. 7 is a detail of the die which simultaneously forms the bifurcations on one end 75 of the shank of the metallic fastening and separates the fastening from the strip of stock, and

Fig. 8 is a detail in perspective, partly in section, of a finished shoe provided with 80 the metallic fastening inseam embodying the features of the present invention.

In the illustrated embodiment of the invention an insole 1 is provided with a series of slashes 2 which are formed normal to one 85 face 3 of the insole along the peripheral margin thereof. The slashes 2 are herein termed "cuspidate slashes" for the reason that the pair of curved cuts 4 in meeting, form a cusp 5. If it is considered desirable for the slash on the sole to form a true geometrical cuspidal curve, then the common tangent of the curved cuts 4 should be radial to the peripheral edge of the sole adjacent the slash. The insole is also provided with a series of awl cuts 6 (Figs. 3 and 4) each one of which extends parallel to the slashed face of the sole from the edge face 7 of the insole to one of the slashes 2 which it intersects below the surface of the 100 insole. The cuspidate slashes and awl cuts are formed normal to the face 3 and edge face 7 of the insole, respectively, and to that end the slashing and cutting tools are maintained at right angles to each other as 105 their points of operation are transferred around the insole.

With the sole thus prepared it may be united to a shoe upper and welt in any suitable manner found desirable or expedient. 110

Preferably the insole is tacked to a last 8 (Fig. 2) and then an upper 9 is lasted to the edge face 7 of the insole in accordance with the method of lasting described by me in my United States Patent No. 1,261,741, dated April 2, 1918. In accordance with the method of lasting described therein the upper 9 is updrawn to bring it to the wood of the last and the updrawn upper is secured by cement to the edge face of the insole. After the lasting operation, a welt 10, which has previously been provided with a longitudinal slit 11, is assembled with the lasted shoe in such a position that the contacting faces of the welt and upper and of the upper and edge face of the insole are arranged in parallel planes normal to the face 3 of the insole (Fig. 3) and also with the unexposed faces of the welt and insole in the same plane.

The upper, insole and welt are united by a metallic fastening inseam comprising metallic fastenings having a shank 12 terminating at each end in a pair of legs 13 turned backwardly into the stock, one pair of legs being clenched in the base of the slit 11 in the welt and the other pair being clenched in the insole. The metallic fastenings are each located in a plane passing through the insole intermediate its top and bottom faces thus producing a hidden inseam located entirely within the material of the welt and insole.

After the inseaming operation, the upper standing skirt of the upper 7 is trimmed, preferably by the machine disclosed in my United States Patent No. 1,373,403, dated April 5, 1921, and the outsole 14 (Fig. 8) is laid upon the welted shoe and secured to the welt 10 by a line of stitches 15.

While in its broadest aspects the invention contemplates providing the insole with cuts and slashes before the fastening inserting operation, it is preferred to form the cuts and slashes in the machine which forms and inserts the metallic fastenings. To this end the metallic fastening inserting machine preferably is provided with an awl 16 arranged to reciprocate in the plane of the slit 11 and cut an awl hole through the base of the slit 11, upper, and edge face 7 of the insole into the body portion of the insole in a direction parallel to the face 3. After the awl 16 forms its cut it is withdrawn and a gouge 17, having an anvil 18 formed thereon, is driven in a direction normal to the face 3 of the insole into the body portion of the insole thus forming a slash intersecting the cut below the surface of the insole.

In the meantime the metallic fastening is being formed in readiness for insertion into the awl hole. To this end the machine carries a metallic strip 19 (Fig. 19) comprising a bar of brass, aluminum or steel, for instance, having substantially a rectangular

cross section. The machine is also provided with a tool or die 20 (Fig. 3) for forming a fastening and separating it from the strip 19. The die 20 is provided with a cross-shaped cutting surface 21 which cuts a cross-shaped piece out of the strip 19 thus forming the legs 13 in the opposed ends of adjacent fastenings and separating a completely formed fastening 22 from the strip of stock (Fig. 5).

After the formed fastening 22 has been inserted into the awl hole 6 the awl 16 is again advanced (Fig. 3) to cause its front end to enter between the outside legs 13 and thus cause them to spread slightly and at the same time drive the inside legs 13 against the anvil 18 and thus initiate the spreading of the inside legs 13. Thereafter the guide 23, for the awl, is advanced to engage its front end between the slightly spread outside legs 13 and drive the fastening home so that the outside and inside legs thereof will clench backwardly into the base of the slit in the welt and the body portion of the insole, respectively, (Fig. 4). With this mode of operation the opposite ends of the fastening are completely buried in the work. The anvil 18 is then removed and the work is fed to locate the tools for the insertion of another fastening.

Clenchable metallic fastenings have been used heretofore to unite component parts of shoes. These clenchable metallic fastenings comprise a single shank terminating at one or both ends with a clenching leg bent backwardly towards the shank. This leg is clenched in the stock by driving the point of the fastening against a segmental anvil held against one of the parts to be united. With this construction and mode of operation the length of the leg is determined solely by the characteristics of the fibre in the stock operated upon as it is apparent that when the fastening is driven into a soft spot the leg will bend easier and to a greater extent than when the fastening is driven into a hard spot. Obviously it is impossible, with the prior art clenchable metallic fastenings, to accurately predetermine the juncture between the shank and the clenching leg and thus obtain a series of metallic fastenings in the united parts having their shanks and clenching legs of uniform length, respectively.

In the present case the bending of the legs 13 is produced by a tool inserted between the legs of a fastening having its crotch backed by the shank which is sufficiently substantial to withstand, without buckling, the leg bending pressure exerted by the tool, and consequently the extent and direction of bend of the legs are independent of the characteristics of the stock being united. By this construction and mode of operation it is possible to produce a series

of metallic fastenings having shanks and clenching legs of uniform length, respectively.

While it is preferred to employ the specific construction, arrangement, mode of operation and method of manufacture shown and described, it will be understood that this specific construction, arrangement, mode of operation and method of manufacture are not essential nor is the conjoint use of all the features of the invention essential except so far as specified in the appended claims, and it may be varied or modified without departing from the broader features of the invention.

It will be also apparent to those skilled in the art that certain features of the present invention are useful in the manufacture of other kinds of shoes than welt shoes; therefore, the term "sole" used in the following claims must be construed to mean any kind of a sole whether an insole or an outsole.

What is claimed as new, is:

25. 1. A sole provided with a series of marginal cuspidate slashes normal to one face thereof.
2. A sole provided with a series of cuspidate slashes normal to one face thereof, and a series of slits formed in the edge face of the sole, parallel to the slashed face of the sole, each slit being arranged to intersect one of the slashes beneath the surface of the sole.
25. 3. A sole provided with a series of slashes each comprising a cuspidal curve having a common tangent formed on the surface of the sole, said curve having the common tangent thereof radial to the adjacent peripheral edge of the sole.
4. A shoe comprising an upper, an unchanneled insole, a welt, a metallic fastening seam uniting said parts comprising metallic fastenings located in a plane passing through the edge of the insole intermediate its top and bottom faces, and an outsole secured to the welt.
5. A shoe comprising an insole, an upper fastened to the edge face of the insole, a welt, a metallic fastening seam uniting the welt to the lasted shoe, and an outsole secured to the welt.
6. A shoe comprising an upper, an unchanneled insole, a welt, a metallic fastening seam uniting said parts comprising metallic fastenings having the opposite ends thereof anchored in the body portion of the welt and insole, respectively, between the surfaces thereof, and an outsole secured to the welt.
60. 7. A shoe comprising an insole, an upper, a welt, a metallic fastening seam uniting said parts comprising bifurcated metallic fastenings having one end double clenched in the body portion of the insole, and an outsole secured to the welt.

8. A shoe comprising an insole, an upper, a welt, a metallic fastening seam uniting said parts comprising bifurcated metallic fastenings having one end double clenched in the interior of the welt, and an outsole secured to the welt.

9. A shoe comprising an insole, an upper, a welt, a metallic fastening seam uniting said parts comprising bifurcated metallic fastenings having both ends double clenched within the body portions of the insole and welt, respectively, and an outsole secured to the welt.

10. A shoe comprising an insole, an upper, a welt, a metallic fastening seam uniting said parts within the body portions thereof comprising metallic fastenings bifurcated at both ends having their top and bottom faces arranged in parallel planes, and an outsole secured to the welt.

11. A shoe comprising an insole, an upper, a welt, a metallic fastening seam uniting said parts comprising metallic fastenings having their top and bottom faces arranged in parallel planes, parallel and intermediate to the top and bottom faces of the insole, and an outsole secured to the welt.

12. A shoe comprising an upper, an insole, a welt, a metallic fastening seam uniting said parts comprising metallic fastenings having one end bifurcated and clenched within the body portion of the insole, and an outsole secured to the welt.

13. In a shoe comprising an upper, an insole and an ungrooved welt, a metallic fastening seam uniting said parts comprising metallic fastenings having one end bifurcated and clenched within the welt and its other end projecting through the edge of the welt and into the insole.

14. In a shoe comprising an upper and a welt, a metallic fastening seam uniting said parts comprising metallic fastenings having both ends bifurcated one end being clenched within the body portion of the insole and the other end being clenched in the welt.

15. A shoe comprising an upper, an insole, a welt split longitudinally along its exposed face, a metallic fastening seam uniting said parts comprising metallic fastenings anchored within the insole and in the base of the slit in the welt, and an outsole secured to the welt.

16. In combination, two members secured together by a metallic fastening of strip form bifurcated at both ends inserted entirely through only one of the members with one end buried from sight in one member, and with the other end buried from sight in the other member.

17. In combination a welt and a member secured thereto by a headless metallic fastening having one end anchored within the body portion of the welt and the other end

- anchored in the member, the end anchored in the welt being bifurcated.
18. In combination, component shoe parts united by means of a fastening inserted through only one of the parts, said fastening having a shank provided with a pair of clinching points turned backwardly toward the shank and buried from sight in the stock at each end of the shank.
19. In combination, component shoe parts united by means of a fastening inserted through only one of said parts, said fastening having a shank rectangular in cross section and provided with a pair of clinching points turned backwardly and buried from sight in the stock at each end of the shank.
20. In combination, component shoe parts secured together by a series of double clinched metallic fastenings inserted through only one of said parts and buried from sight in both parts, the shanks of the fastenings being uniform in length throughout the series.
21. That improvement in the art of preparing soles for the inseaming operation which consists in slitting the sole through its edge face and parallel to the surfaces thereof, and intersecting said slit by a cuspidate slash through one surface of the sole having its cusp directed outward.
22. That improvement in the art of preparing soles for the inseaming operation which consists in slitting the sole by a cut penetrating through its edge face and having a definite width, and intersecting said slit by a cuspidate slash through one surface of the sole having its cusp positioned substantially centrally of the width of said slit.
23. That improvement in the art of preparing soles for the inseaming operation which consists in producing a series of independent, marginal slits, each having a greater length than width, by cuts penetrating the edge surface of the sole, and producing independent cuspidate slashes through one surface of the sole which are of a depth sufficient to intersect said slits and so located that each cusp is positioned substantially centrally of the width of a slit and is directed outward.
24. A shoe comprising an upper, an unchanneled insole and a welt arranged with their unexposed faces in the same plane, a metallic fastening seam uniting said parts, and an outsole secured to the welt.
25. That improvement in the art of uniting component shoe parts which consists in inserting below the surface thereof the shank of a fastening having bifurcated ends, said shank extending through only one of the parts, and spreading the legs of the bifurcated ends apart and bending them backwardly into the parts whereby the parts are secured together by a fastening having a pair of double clinched points connected by a shank buried from sight within the parts.
26. That improvement in the art of inseaming welt shoes which consists in assembling a welt with an upper and an insole, and inserting metallic fastenings through said parts in a plane passing through the edge of the insole intermediate its top and bottom faces.
27. That improvement in the art of making welt shoes which consists in lasting an upper to the edge face of an insole, attaching a welt to the lasted shoe by a metallic fastening seam, and securing an outsole to the welt.
28. That improvement in the art of preparing soles for the inseaming operation which consists in slitting the body portion of the sole through the edge face thereof, and intersecting the slit in the sole below the surface thereof by a cuspidate slash normal to said slit.
29. That improvement in the art of uniting component shoe parts which consists in awling through the parts, driving an anvil into one of the parts perpendicular to the awl cut, placing a metallic fastening bifurcated at both ends into the awl cut, and inserting an instrument between the legs of the bifurcations at one end of the fastening to drive the other end of the fastening against the anvil and thus cause the anvil to clench one end of the fastening in one part and the instrument to clench the other end of the fastening in another part.
30. That improvement in the art of uniting component shoe parts together which consists in awling through the parts, driving an anvil into one of the parts perpendicular to the awl cut, placing a fastening bifurcated at both ends into the awl cut, forcing the awl, or a separate instrument, between the legs of the bifurcation at one end of the fastening to drive the other end of the fastening against the anvil to initiate the spreading apart of the legs at both ends of the fastening, and jamming another instrument between the partially spread legs at one end of the fastening to forcibly press the fastening against the anvil to complete the spreading apart of the legs at both ends of the fastening and thus cause the legs to clench in the parts.
31. That improvement in the art of making welt shoes which consists in slitting a welt longitudinally along one edge face; assembling the welt with a lasted shoe comprising an insole and an upper secured to the edge face thereof; inserting metallic fastenings through the welt, upper and insole, and securing an outsole to the welt.
32. That improvement in the art of making welt shoes which consists in slitting a welt longitudinally along one edge face; assembling the welt with a lasted shoe com-

prising an insole and an upper secured to the edge face thereof; and with the unslit edge face of the welt, the opposite faces of the marginal portion of the upper and edge 5 face of the insole in parallel planes normal to the face of the insole, inserting metallic fastenings through the welt, upper, and insole, and securing an outsole to the welt.

33. That improvement in the art of making welt shoes which consists in assembling a welt with a lasted shoe comprising an insole and an upper secured to the edge face thereof with the contacting faces of the welt and upper and of the upper and insole in parallel planes normal to the face of the insole, inserting metallic fastenings through the welt, upper and insole and securing an outsole to the welt.

34. A shoe comprising an upper, an unchanneled insole and an ungrooved welt having their edge surfaces opposite to each other, an inseam comprising metallic fastenings extending through said edge surfaces and the interposed upper, having the opposite ends thereof anchored in the interior of the welt and insole, and an outsole secured to the welt.

35. The step product in the manufacture of shoes comprising a lasted, unsoled shoe having an upper, an insole and a welt on opposite sides of said upper with their lower surfaces in the same plane and their edge surfaces adjoining the upper, and an inseam comprising metallic fastenings extending through said upper and adjacent portions of the welt and insole having the ends thereof clenched in the interior of the welt and insole.

36. The step product in the manufacture of shoes comprising a lasted, unsoled shoe having an upper, an insole and a welt on opposite sides of said upper with their lower surfaces in the same plane and their edge surfaces adjoining the upper, and an inseam comprising metallic fastenings extending across the joints formed by the welt, upper and insole and completely embedded in said materials.

37. In a shoe of the type in which the edge face surfaces of the welt and insole adjoining the upper at opposite sides thereof with their lower surfaces in the same plane, the combination of marginal shoulders provided on the interior of said welt and insole, and a metallic fastening extending through said edge surfaces and having its ends anchored against said shoulders, whereby the fastening is completely embedded in said materials.

38. In a shoe, a welt and an insole secured together by a metallic fastening bifurcated at both ends, and having one end buried from sight and anchored in the welt and

the other end buried from sight and anchored in the insole.

39. In a shoe, a welt and an insole united edge face to edge face by means of a fastening having a shank provided with a pair of clenching points at each end of the shank turned backwardly into the welt and insole.

40. A sole provided with a series of marginal cuspidate slashes normal to one face thereof, and a like number of marginal slits substantially midway the sole thickness and communicating with said slashes.

41. A sole provided with a series of cuspidate slashes normal to one face thereof and having their cusps directed outward, and a series of slits formed through the edge face of the sole in a direction to intersect each of the slashes beneath the slashed face of the sole.

42. A sole provided with a series of slashes each comprising a cuspidal curve having a common tangent formed on one surface of the sole, said curve having the common tangent thereof radial to the adjacent peripheral edge of the sole, and a series of slits extending from the edge of the sole to said slashes radial in a like manner.

43. That improvement in the art of uniting component shoe parts which consists in inserting the shank of a fastening into said parts, driving an instrument against one end of the fastening to cause the other end of the fastening to engage an anvil and clench in the work, and then driving another instrument against the first named end of the fastening to cause it to clench in the work.

44. That improvement in the art of uniting component shoe parts which consists in inserting the shank of a fastening having bifurcated ends into said parts, driving an instrument against one end of the shank of the fastening to cause the other end to engage an anvil and clench in the work, and then driving another instrument between the bifurcations on the first named end of the fastening to cause it to clench in the work.

45. A welt shoe, having in combination, an upper, a welt slit along one longitudinal edge to provide an interior shoulder, an insole provided with an interior shoulder, and means for securing the upper, welt and insole together comprising an inseam engaged with the interior shoulders on the welt and insole and arranged in a plane parallel and intermediate the top and bottom faces of the insole.

In testimony whereof I have signed my to this specification.

CHARLES C. BLAKE.
